UNITED STATES PATENT OFFICE.

STANLEY L. CONNELL, OF GIRARD, PENNSYLVANIA, ASSIGNOR TO THE GIRARD MODEL WORKS, INC., OF GIRARD, PENNSYLVANIA, A CORPORATION OF PENNSYLVANIA.

SPINNING TOP.

Application filed January 5, 1924. Serial No. 684,541.

To all whom it may concern:

Be it known that I, STANLEY L. CONNELL, a citizen of the United States, and resident of Girard, in the county of Erie and State of Pennsylvania, have invented certain new and useful Improvements in Spinning Tops, of which the following is a specification.

This invention relates to a spinning top, and relates more particularly to an improved sheet metal top of the type embodying a top body and a spring twisting or spinning head which is energized for setting the top into spinning action.

In a well-known form of this type of spinning top, the top body is provided with a stem which receives the twisting or spinning head; and the latter includes a spring element designed and constructed to engage the top body so that the same may be wound or energized when the spinning head is rotated on the top body. The twisting head and top body are further provided with interengaging locking means for locking the spinning head in energized condition on the spinning top. In this form of top construction the spring element usually consists of a coil spring which is arranged to receive and surround the stem of the top; and to release the top to set the same into spinning action, it is necessary to force the stem relatively to and through the main body of the twisting or spinning head and also bodily through the coil spring; and due to the necessity of thus moving the stem through the spinning head, it oft-times is difficult to effect the release and the spinning of the top body, this being especially so when the spring is substantially fully wound, in which condition the coil spring being wound taut about and being in frictional engagement with the stem, resists and opposes the releasing movement of the stem. The prime desideratum of my present invention comprehends the provision of an improved twisting or spinning device in which this objection is effectively obviated and which is constructed so that the top body may be released and set spinning without the resisting interference of the winding spring and without relatively moving the stem of the top and the main body of the spinning device.

In prior spinning top constructions of the type referred to, the spinning or twisting device is usually provided with a single

locking element, which in the rotation of the spinning device on the top body engages one of a plurality of complementary locking means formed in the top body. I have found in this form of structure that when the twisting head is energized to a substantial degree, the spinning device has a tendency to assume an unbalanced position with its axis at an angle to the axis of the top stem, rendering the locking means ineffectual and insecure. It is a further principal object of my present invention to provide an improved spinning device construction in which this unbalancing tendency is eliminated, and more specifically in which a plurality of interengaging locking means are provided to maintain the spinning head and top stem always coaxial to assure a balanced behavior of the spinning device and proper locking interengagement between the parts.

Another problem in the design of a serviceable spinning device correlative to that of obtaining ease of release or disengagement of the same from the top body for permitting a maximum convenience and facility of top spinning operation, is that of providing for an efficient "hold" or finger grasp so as to permit a child to obtain a proper and effectual "purchase" on the parts of the spinning device to operate the same. A still further principal object of my present invention includes the provision of an improved twisting head or device in which the parts are so constructed and inter-related as to provide a finger grasp which affords a security of "purchase" and a convenience and facility of operation.

A still further desideratum of the present invention centers about the provision of an improved spinning top body. In spinning tops of the present type, as shown for example in the patent to E. W. Gibbs, No. 847,933 of March 19, 1907, a disk is provided which is joined interiorly to the top body to produce an air-tight seal therewith, the stem of the top having a part extending from the bottom of the top to the said disk being utilized for holding the disk in the desired position. I have found that when this form of top is dropped upon a support for spinning, the upward axial thrust which is produced and which is effective on the stem is insufficiently resisted by the disk, with the result that the disk becomes distorted in use and the stem becomes axially loosened.

To inhibit this tendency and to prevent any axial displacement of the stem, my invention includes the provision of a supporting element for the stem which is shaped or constructed to present an axial component of force which resists or opposes the upward thrust of the stem, so that all the parts are maintained intact even after long periods of use.

10 To the accomplishment of the foregoing and such other objects as may hereinafter appear, my invention consists in the elements and their relation one to the other, as hereinafter particularly described and 15 sought to be defined in the claims; reference being had to the accompanying drawings which show a preferred embodiment of my invention, and in which:

Fig. 1 is an elevational view of my improved spinning top.

Fig. 2 is a plan view thereof,

Fig. 3 is an enlarged cross-sectional elevational view thereof,

Fig. 4 is a plan view of the top body,

25 Fig. 5 is a view in perspective of the parts of the spinning head showing the manner of assembling the same, and

Fig. 6 is a development view of the top stem showing the manner of fashioning the 30 same.

Referring now more in detail to the drawings, the spinning top of my invention comprises an improved spinning top body and an improved spinning head or device B receivable by the top body A and rotatable relatively thereto in a well known manner to effect the energization of the spinning head and the rotation or spinning of the top.

The top body A comprises the oppositely 40 concaved body sections 10 and 11 made of sheet metal joined peripherally at 12, the body section 10 being preferably, though not necessarily, provided with a raised central portion 13, which latter is provided 45 with the circumferentially arranged orifices 14 and the circumferentially arranged indentations 15 for a purpose which will appear clearer hereinafter. Supported centrally in the body sections 10 and 11, there 50 is provided the stem 16 which in the present form of my invention preferably extends from the lower body section 11 through and above the upper body section 10, the stem being provided with a shoulder portion such 55 as the bead 17 engaging the lower rim of a partitioning member 18, for supporting the same for effecting an air-tight joint with the upper body section 10, so that an influx of air through the orifices and indentations 60 14 and 15 is prevented so that when the air holes or orifices 19' are provided in the top body, a humming sound will be produced when the top is spun.

As heretofore mentioned, I have found 65 that when the top is dropped upon a sup-

port, an upward axial thrust is produced on the stem 16 which is ineffectually resisted in prior constructions by the division member 18, so that an axial displacement or "play" is produced in the stem after a short 70 period of use. To eliminate this objection, I have found it desirable to provide means for producing a counter or opposing axial thrust, and I have found that when the division member 18 is made or fashioned in 75 a frusto-conical shape, as clearly shown in Fig. 3 of the drawings, an opposing axial component of force is produced sufficient to obviate any tendency to displacement of the stem. This frusto-conical member 18 is 80 made of sheet metal and is arranged as shown with the rim 19 of its large base seated in the depression provided by the raised portion 13, and with the rim 20 of its small base securely engaged by the shoulder 85 17 of the stem.

In order to prevent any lateral displacement of the stem during use, I have also found it desirable to modify the construction of the bottom of the stem, and in the 90 present form of my invention the stem 16 is provided at its bottom with a portion 21 of reduced area designed so as to surround and "snugly" fit the shank 22 of the spindle or spinning peg 23 as shown in Fig. 3 of the drawings, and preferably the stem is also provided with the oppositely arranged radial wings 24, 24 for obtaining a secure support. This stem may be obviously produced in any desired manner, and in Fig. 6 of the drawings I show a preferred method of 95 making the same, the stem being fashioned out of a blank of sheet metal having the parts 16' and 16² joined centrally of the parts 16³ which latter forms the top of the stem, the bottom of each blank part being bent along the lines a, a to produce the wings 24, 24 and the remainder of the blank parts being fashioned by suitable dies to produce the tubular shape of the body of the stem and the tapered shape of the bottom thereof.

As heretofore referred to, it is an object of the invention to provide an improved spinning device constructed so that the top body may be released therefrom and set into spinning action without having to overcome the resisting interference of the winding spring and without the necessity of effecting any relative motion between the stem of the top and the main body and spring of the twisting or spinning head, this so as to eliminate the difficult spinning operation incident to prior devices. To accomplish this object of the invention, the spinning head B in its broader aspects comprises a body section b' and a locking element b² which in its more specific aspects may comprise a second body section of the spinning device 110 movably carried by the body section b' and 115

- arranged to engage the spinning top for locking the body section thereon in an energized condition, the locking element or second body section b^2 being movable relatively to the top and relatively to the body section b' so as to effect a release of the top without the necessity of imparting relative motion between the top stem 16 and the spinning body section b' .
- 5 In the preferred construction, the body section b' includes a vertically arranged barrel portion 25 and a horizontally arranged plate portion 26 preferably shaped to present the opposite wings 26' and 26², a marginal depending flange or skirt portion 26³, and a central thumb engaging portion 26⁴, the barrel and plate portions being secured one to the other by the tongue and slot means 27. Carried wholly by the body section b' , there is provided the winding spring element 28 which preferably comprises a coil spring arranged within the barrel 25, the upper end of the said spring being attached to the body section, as to the finger 29 struck from the plate 26, the lower end 30 of the said spring element 28 being shaped so as to be free to engage any of the plurality of the orifices 14 in the spinning top.
- 10 The locking element or body section b^2 also preferably includes a vertically arranged barrel portion 31 arranged coaxially with the inner barrel 25 and a horizontal plate portion 32 presenting the opposite wings 32' and 32², the said plate portion being shaped to provide the upturned marginal skirt or flange 32³.
- 15 As clearly shown in Figs. 1 and 3 of the drawings, the opposite wings of the plate portions 26 and 32 are arranged in close overlying relation so as to produce a convenient finger grasp, the marginal flanges of the said plate portions being arranged to telescope and interlock for forming a casting which houses a compression spring 33, the opposite ends of which bear in opposition against the plate sections to hold the same normally in the position shown in Fig. 3 of the drawings.
- 20 The locking element proper in the preferred construction comprises a cup-shaped member 34 attached to the outer barrel 31 by the tongue and groove means 34', the said member 34 being provided peripherally with a plurality of locking teeth 35, 35 arranged to engage and interlock with the indentations 15 of the top body heretofore referred to. By the provision of this locking means, I have found that the body sections b' and b^2 are always maintained in coaxial relation even when the spring element is fully energized, this producing not only a balanced construction but assuring the locking engagement between the spinning top and the spinning head.
- 25 The manner of making and using my improved spinning top and its advantages will in the main be fully apparent from the above detailed description thereof. It will be further apparent that after the spinning device 70 is energized with the parts arranged as shown in Fig. 3 of the drawings, to release the top and spin the same the locking element or body section b^2 is moved upwardly against the action of the compression spring 33, the 75 disengagement of the locking teeth 35 from the top body effecting the release of the top and the spinning of the same under the influence of the recoil action of the spring element 28. It will be noted that this is accomplished without moving the spring element relatively to the stem so that the only force which it is necessary to overcome in spinning the top is that of the compression spring 33 and the slight friction between the inter-engaging locking means 35—15. It will be further noted that by the provision of the plurality of locking teeth and the symmetrical construction of the body sections b' and b^2 , that a highly advantageous balanced spinning device is produced. The provision, moreover, of the opposite wing construction yields a spinning device which presents a finger grasp which may be manipulated by the child with considerable ease and convenience.
- 30 While I have shown my device in the preferred form, it will be obvious that many changes and modifications may be made in the structure disclosed without departing 80 from the spirit of the invention, defined in the following claims.
- I claim:
1. The combination with a spinning top having an upwardly projecting stem, of a top-spinning device comprising a body section for receiving said stem, a spring element carried by said body section and having means for engaging the spinning top, a locking element surrounding and movably carried by the body section arranged to engage the said spinning top for locking the said body section thereon with the spring element energized, and means for moving the locking element relatively to the said body section and in disengagement from the spinning top whereby the spinning top may be released from the energized top-spinning device without any relative axial motion between the said top stem and the top-spinning body section.
- 105 110 115 120
2. The combination with a sheet metal spinning top having an upwardly projecting stem, of a top-spinning device comprising a body section made of sheet metal for receiving said stem, a spring element attached at one end to said body section and being free at the other end for engaging the spinning top, a locking element surrounding and movably carried by the body section ar-
- 85 90 95 100 105 110 115 120 125 130

ranged to engage the spinning top for locking the said body section thereon with the spring element energized, and means for moving the locking element relatively to the 5 said body section and in disengagement from the spinning top whereby the spinning top may be released from the energized top-spinning device without any relative axial motion between the said top stem and the 10 top-spinning body section.

3. A top-spinning device comprising a body section, a spring element carried by said body section and having means for engaging a spinning top, a locking element disposed 15 coaxially with and movably carried by the body section arranged to engage the said spinning top for locking the said body section thereon with the spring element energized, and means for moving the locking 20 element relatively to the said body section to disengage the element from the spinning top to release the latter without moving the 25 said body section.

4. The combination with a spinning top 30 having an upwardly projecting stem, of a top spinning device removably receivable by the said stem, the said top spinning device comprising coaxially arranged body sections one movable axially relatively to the other, 35 a winding spring element carried wholly by one of said body sections and having means for engaging the spinning top, and a locking element on the other of said body sections arranged to engage the said spinning 40 top for locking the said body section thereon with the spring element energized.

5. A top-spinning device comprising coaxially arranged body sections, one section being axially movable relatively to the other, 45 a spring element attached at one end to one of said body sections and being free at the other end for engaging a spinning top, and a locking element on the other of said sections arranged to engage the spinning top for locking the first body section thereon when 50 the spring element is energized.

6. A top-spinning device comprising coaxially arranged body sections one movable axially relatively to the other, the said sections including inner and outer barrel portions, a coil spring element carried by one 55 section and arranged within the inner barrel portion and a locking element on the outer barrel portion having a plurality of locking teeth arranged circumferentially thereabout.

7. A top-spinning device comprising two body sections axially movable one relatively to the other, each section including a vertical barrel portion and a horizontal plate 60 portion, the barrel portions being coaxially arranged and the plate portions being arranged one overlying the other to form a finger grasp for relatively moving the body sections, a spring element carried by one of

said body sections and a locking element 65 carried by the other body section.

8. A top-spinning device comprising two body sections axially movable one relatively to the other, each section having a barrel portion and opposite wing portions, the barrel portions of the sections being arranged coaxially and the wing portions being arranged in overlying relation to form a finger grasp for relatively moving the sections, a 70 spring element carried by one of said sections and a locking element carried by the other of said sections.

9. A top-spinning device comprising two body sections axially movable one relatively to the other, each section having a barrel portion and opposite wing portions, the barrel portions of the sections being arranged coaxially and the wing portions being arranged in overlying relation to form a finger 75 grasp for relatively moving the sections, a spring between the body sections, a spring element carried wholly by one of said body sections and a locking element on the other body section.

10. A top-spinning device comprising two body sections axially movable one relatively to the other, each section having a barrel portion and opposite wing portions, the barrel portions of the sections being arranged coaxially and the wing portions being arranged in overlying relation to form a finger grasp for relatively moving the sections, a compression spring located between the wing portions, a coil spring attached at one end 80 to one of said body sections and being free at its other end to engage a spinning top, and a locking element on the other body section.

11. A top-spinning device comprising relatively movable body sections one body section including an outer barrel and a plate attached thereto, the said plate being provided with an upturned marginal flange, the other body section including an inner barrel and a plate attached thereto, the said latter plate overlying the first-mentioned plate and being provided with a downwardly turned marginal flange arranged in telescopic relation with the upwardly turned flange of the first-mentioned plate and providing therewith a housing, a compression spring in said housing between said plates, a coil spring within the inner barrel having one end attached to the overlying plate and being free at its other end to engage a spinning top, and a locking element attached to the outer barrel provided with a plurality of peripheral locking teeth.

12. The combination with a spinning top having an upwardly projecting stem, of a top-spinning device comprising a body section for receiving said stem, a spring element carried by said body section having

- means for engaging the spinning top and a locking element movably carried by the body section, said locking element having a plurality of peripherally spaced locking means 5 arranged to engage the spinning top at points spaced about said stem for locking the said body section thereon when the spring element is energized.
13. The combination with a spinning top 10 having an upwardly projecting stem, of a top spinning device removably receivable by said top stem and comprising a body section including a horizontally arranged plate portion, a winding spring element associated 15 with said body section and having means for engaging the spinning top, and a locking element associated with said body section also arranged to engage the said spinning top, the said locking element being also provided with a horizontal plate portion, the 20 said plate portions being arranged one overlying the other for forming a finger grasp to move the locking element relatively to the body section.
- 25 14. The combination with a spinning top having an upwardly projecting stem, of a top spinning device removably receivable by said stem and comprising a body section having oppositely disposed wing portions, 30 a winding spring element carried by said body section and having means for engaging the spinning top, a locking element associated with said body section arranged to engage the said spinning top and also provided with oppositely disposed wing portions 35 underlying the wing portions of the body section and forming therewith a finger grasp for moving the locking element relatively to the body section.
- 40 15. A sheet metal spinning top comprising upper and lower body sections connected to form a hollow body, a frusto-conical shaped member arranged with its large base 45 interiorly engaging the top of the upper body section and a stem disposed centrally of said sections and member, the said stem having an end interiorly engaging the bottom of the lower body section and having a shoulder arranged substantially below the 50 top of the upper body section and engaging the small base of the frusto-conical member, the construction being such that an upward axial thrust on said stem incident to the dropping of the spinning top upon a support will be resisted by the downward axial component of force provided by said frusto-conical member. 55
16. A spinning top comprising upper and lower body sections made of sheet metal connected to form a hollow body, a frusto- 60 conical shaped member also made of sheet metal arranged with the rim of its large base interiorly engaging the top of the upper body section and forming therewith an air-tight joint, and a stem supported 65 centrally of said sections and member, the said stem having an end interiorly engaging the bottom of the lower body section and having a bead arranged substantially below the top of the upper body section and engaging the rim of the small base of the frusto- 70 conical member, the construction being such that an upward axial thrust on said stem incident to the dropping of the spinning top on a support will be effectively resisted 75 by a downward axial component of force provided by said frusto-conical member. 75
17. A spinning top comprising upper and lower body sections connected together to form a hollow body, a spindle in said lower 80 body section having an interiorly disposed shank, a frusto-conical member arranged with its large base interiorly engaging the top of the upper body section, and a stem disposed centrally of said sections and member, the bottom of said stem receiving and closely fitting the spindle shank to prevent lateral displacement of the stem, the said stem being provided with a shoulder arranged substantially below the top of the 85 upper body section and engaging the lower base of the frusto-conical member, the construction being such that an upward axial thrust on said stem incident to the dropping of the spinning top on a support will be effectively resisted by a downward axial component of force provided in the frusto-conical member, preventing any axial displacement of the stem during use. 90
- Signed at Girard, in the county of Erie 100 and State of Pennsylvania, this 26th day of December, A. D. 1928.

STANLEY L. CONNELL.
